COLLAPSIBLE GANTRY

Robert J. Bushong and James L. Montgomery,
Indianapolis, Ind., assignors to Insley Manufacturing Corporation, Indianapolis, Ind., a corporation of Indiana

Application May 5, 1953, Serial No. 353,118

9 Claims. (Cl. 212—59)

1

This invention relates to cranes or like machines which are adapted to travel from place to place and which may be equipped with hoisting, swinging, or excavating mechanism.

This invention is more specifically concerned with such machines which have a collapsible or lowerable A frame or gantry so that the crane or like machine may pass under an overhead clearance less than the overall height of the gantry when positioned for efficient operation of the crane boom, or when the crane is to be shipped or transported under its own power.

An object is to provide a crane with a high A frame or gantry, which can be raised to a most efficient position of use or lowered for transportation purposes by operation of the boom after the simple manipulation of fastening devices and without employment of any outside assistance or devices.

Other objects of the invention will herein-after appear, and, for purposes of illustration but not of limitation, an embodiment of the invention is shown on the accompanying drawings, in which:

Figure 1 is a side elevation of a crane showing the lowerable or collapsible gantry in its raised position and the parts in position for normal operation of the boom and fall block;

Figure 2 is an end elevation substantially on the line 2—2 of Figure 1;

Figure 3 is a view similar to Figure 1, but showing the boom in its raised position such as to enable the tube and pipe which serves as a connection between the boom and the gantry to be fixed, preparatory to a collapsing or lowering of the high gantry;

Figure 4 is an enlarged fragmentary perspective view showing particularly the connection between the rear legs and the bracket which enables pivotal movement of certain of the legs by removal of pins when the collapsible gantry is lowered; and

Figure 5 is a view similar to Figure 1, but showing the collapsible gantry in its collapsed or lowered position.

The illustrated embodiment of the invention comprises a supporting platform 10 which is mounted on a turntable 11 carried by a truck frame 12. The truck frame 12 is mounted on rubber tired wheels 13 and propelled by any suitable means, not shown. At the front end of the platform 10 is a pair of laterally spaced brackets 14, only one of which is shown, and to which is pivotally mounted the lower end of the boom 15, the lower end being furcated for pivotal

2

mounting to the brackets 14, as will be readily understood by those skilled in this art.

Mounted on the platform 10 is an upright stationary support having a pair of laterally spaced upright rear legs 16 which, as shown of Figure 2, have an intermediately arranged X brace 17 for rigidifying the structure. The lower ends of the legs 16 are suitably secured to the platform structure 10 by fasteners 18. At the upper ends of the legs 16 is a transversely arranged shaft 19 carrying sheaves 20, a pair being arranged at each end of the shaft and a cable guard 20a overhanging each pair of sheaves as shown. Inclining downwardly and forwardly from the shaft 19 adjacent opposite ends thereof are brace rods 21, which are connected at their lower ends to leg supporting plates 22 respectively.

The lower ends of the legs 21 have extensions which are disposed between the leg supporting plates, a pair of such plates being associated with each of the leg extensions, and pins 23 and 24 secure the leg extensions to the plates 22 and also serve as a connecting means between the assembly and the adjacent bracket 14. Integral with each of the plates 22 is an upwardly and rearwardly inclined extension 25 and fitting between each pair of extensions 25 is a front leg 28, a pin 26 extending through the adjacent extensions 25 and the respective leg 28, providing a pivot for the associated leg 28.

The upper end of each of the legs 28 is pivotally mounted on the pins 29. Also pivotally mounted on the pins 29 are rods 30 which telescope into sleeves 31. The outer ends of the sleeves 31 are connected to brackets 32 fixed to the boom 15. Thus each side of the boom 15 is connected through a telescoping sleeve and rod to the pin 29. In each rod 30 adjacent its inner end is a hole 30a and adjacent the inner end of the telescoping sleeve is a hole 31a and these two holes may be brought into registration to allow a pin 300 (Figure 3) to be inserted so as to secure these parts against free telescoping movement during the lowering and raising of the upper or collapsible gantry as will hereinafter appear.

Mounted on the lower or stationary A frame is an upper collapsible or lowerable gantry which has a pair of laterally spaced rear legs 33. The legs 33 are braced by an X frame 34 and on the upper ends of the legs 33 is a transverse shaft 35 on which are mounted sheaves 36 arranged in pairs at opposite ends. Over each pair of sheaves is disposed a cable guide 35a. Pivotally mounted on the shaft 35 adjacent each end thereof is a relatively short arm 37 and the

lower end of each arm is normally held to the adjacent leg 33 by a pin 38, which is removable when the upper gantry is lowered, as will herein-after appear. Inclining downwardly and forwardly from each end portion of the shaft 35 is a front leg 39, which has at its lower end a mounting plate or bracket 40, which is pivotally mounted on a transverse pin 29. To brace the parts, an arm 41 is pivotally mounted on each end of the shaft 19 and is connected by a removable pin 42 to the bracket plate 40. When the pin 42 is removed, the arm 41 can swing downwardly and rest on top of the leg 21, as indicated on Figure 3.

The boom 15 is raised by a hoist cable 43, which extends from a power operated winch 44 on the platform 10 about sheaves 36, a sheave assembly 46 and a sheave block 45. The block 45 is connected by a cable 47 to the outer end of the boom 15. Manifestly, operation of the winch in one direction or the other effects a raising or lowering of the boom, as will be readily understood.

Suspended from a sheave 50 on the outer end of the boom 15 by a cable 49 is a fall block 48, the cable 49 extending to a power operated winch 51 mounted on the platform 10. It will be understood that other objects or devices may be attached to the boom, such as a drag line bucket and the like.

In order to lower the upper A frame from the position shown in Figure 1 to that shown in Figure 5, the boom 15 is raised substantially to the position shown in Figure 3, so that the holes 31a and 30a in the telescoping tubes 31 and rods 30 are in registration so that the pins 300 can be inserted into these holes. It is then necessary to remove the pins 38 which enable the arms 37 to hang free on the shaft 35. Thereupon the pins 42 are removed so that the arms 41 swing downwardly and rest upon the legs 21. The upper A frame is now capable of being lowered, and this is accomplished by lowering the boom 15.

It will be thus understood that the collapsible A frame or gantry is lowered under control of and by the boom as the latter swings downwardly with the articulated arms 28 and 39 rocking forwardly. After the A frame has been lowered, the pins 38 are employed to secure the arms 37 by insertion in the same holes in the plate extensions 25. Thus the collapsible A frame is now held in its fixed lowered position and the pin 300 may be removed to enable relative movement of the telescoping members 30 and 31 so that the boom can, if desired, be lowered to the ground. The boom can be carried by the A frame in its lowered position for traveling purposes.

In order to raise the upper or collapsible A frame or gantry, the pins 300 are first inserted in the boom backstops. Then the pins 38 are removed from the arms 37. Thereafter, by raising the boom 15, the upper A frame is accordingly raised by the rearward pushing movement effected by the boom backstops (the telescoping members 30 and 31). After the A frame has been raised to the desired position, the pins 42 are applied to connect the arms 41 to the bracket plates 40 by inserting same in the aligned holes in the arms 41 and the plates 40. Finally, the pins 38 should be inserted through the registering holes in the arms 37 and 33. By removing the pin 300 from the telescoping backstop parts 30 and 31 so that the boom backstop is free to move along with the boom, the machine is ready for operation.

An important feature of the above structure resides in the provision of a collapsible or lowerable A frame or gantry which is raised or lowered by the boom without the addition of cables or outside connection. Manifestly, nothing is added or removed in the above assembly except pins which can be quickly and conveniently applied or removed as the need arises.

It is to be understood that numerous changes in details of construction, arrangement and operation may be effected without departing from the spirit of the invention especially as defined in the appended claims.

What we claim is:

1. In a crane, a boom mounted for up and down swinging movement, a high A frame, including pivotally mounted legs, and a pair of vertically disposed articulated arms, a connection between the jointure of the said arms and said boom, and hoist means for controlling the raising and lowering of said boom, whereby said A frame may be raised or lowered by raising and lowering of said boom.

2. In a crane, a boom mounted for up and down swinging movements, a gantry including a stationary structure and a member mounted on the stationary structure for movement thereon from an elevated position to a lower position, a pair of articulated arms pivoted respectively to the upper end of said member and to said stationary structure, rigid means for releasably retaining said arms against movement, and means providing a connection between the jointure of said arms and said boom for enabling said member to be raised or lowered by raising and lowering movements of said boom upon release of said retaining means.

3. In a crane, a boom mounted for up and down swinging movements, a gantry including a stationary structure and a member mounted on the stationary structure for movement thereon from an elevated position to a lower position, sheaved means on the upper end of said member, boom hoist means including a cable passing over said sheaved means and connected to said boom, a pair of articulated arms pivoted respectively to the upper end of said member and to said stationary structure, rigid means for releasably retaining said arms against movement, and means providing a connection between the jointure of said arms and said boom for enabling said member to be raised or lowered by raising and lowering movements of said boom upon release of said retaining means.

4. In a crane, as claimed in claim 3, in which the connection between the articulated arms and the boom, comprises a pair of telescoping rigid members, and means for securing said member to prevent telescoping movement thereof during raising and lowering of said gantry member.

5. In a crane, as claimed in claim 4 in which said rigid retaining means comprises an arm pivoted at one end to said stationary structure, and a releasable connection between the opposite end of said arm and the juncture of said articulated arms.

6. In a crane, a boom mounted for up and down swinging movements, a gantry including a stationary structure and a member mounted on the stationary structure for movement thereon from an elevated position to a lower position, a pair of articulated arms pivoted respectively to the upper end of said member and to said stationary structure, rigid means for releasably retaining said arms against movement, means providing a connection between the jointure of said arms and

said boom for enabling said member to be raised or lowered by raising and lowering movements of said boom upon release of said retaining means, and means to retain said member in lowered position when the boom is similarly in lowered position.

7. In a crane as claimed in claim 6, in which said retaining means comprises arm means adapted to assume the position of the lowermost of the articulated arms when the latter are outwardly extended upon lowering of the boom, and fastener means for rigidly connecting the lower end of said arm means.

8. In a crane, a boom mounted for up and down swinging movements, a gantry including a stationary structure and a member mounted on the stationary structure for movement thereon from an elevated position to a lower position, a pair of articulated arms pivoted respectively to the upper end of said member and to said stationary structure, pivoted arm means extending from said stationary structure to the jointure of said articu-

lated arms, removable pin means for connecting said last arm means to said jointure, telescoping boom stop means between said boom and the jointure of said articulated arms, means to secure said boom stop against telescoping movement, and pivoted arm means associated with said first member, whereby upon removing said pin means and securing said boom stop and lowering the boom, said first member is lowered and the articulated arms outwardly extended, and thereupon by securing said last pivoted arm means, the gantry is secured in the lowered position.

9. In a crane as claimed in claim 8, in which the stationary structure comprises a rigid A-frame having front and rear leg members.
